COMBINED IRONING BOARD AND STEPLADDER

Filed July 20, 1922

By *J. N. Bryant*
Attorney

UNITED STATES PATENT OFFICE.

PAUL WOSS, OF CHICAGO, ILLINOIS.

COMBINED IRONING BOARD AND STEPLADDER.

Application filed July 20, 1922. Serial No. 576,837.

To all whom it may concern:

Be it known that I, PAUL WOSS, a citizen of the United States of America, residing at Chicago, in the county of Cook and State of Illinois, have invented certain new and useful Improvements in Combined Ironing Boards and Stepladders, of which the following is a specification.

The primary object of this invention is 10 the production of a device of this character that is both simple of operation and inexpensive of manufacture and one wherein the device may be readily folded up and stored in a convenient manner.

15 A further object of this invention is to so construct an article of this nature as to readily enable the same to be so formed as to function as an ironing board, and wherein the same may, by a few comparatively simple 20 operations, be converted into the conventional type of stepladder.

With the above general objects in view the invention consists in the novel combination and arrangement of parts hereinafter 25 more fully described in connection with the accompanying drawings, and in which like reference characters designate corresponding parts throughout the several views.

In the drawing: 30 Fig. 1 is a side elevational view of my invention showing the device set up in position for use as an ironing board,

Fig. 2 is a similar view but showing the same employed as a stepladder;

Fig. 3 is a rear elevational view of the device as shown in Fig. 2, a portion of the same being broken away so as to disclose more clearly the locking elements for one of the pairs of supporting legs.

Fig. 4 is a fragmentary longitudinal cross 40 sectional view upon the line 4—4 of Fig. 1,

Fig. 5 is a vertical sectional view upon the line 5—5 of the same figure, and

Fig. 6 is a fragmentary cross sectional 45 view upon the line 6—6 of Fig. 3 and looking in the direction of the arrows.

Referring more in particular to the several views there is shown an ironing board 1 of any preferred design, and provided 50 with a pair of forward and rearward supporting legs 2 and 3. These supporting legs are formed from spaced side bars 4 and 5 and the bars forming the forward pair of the supporting legs are adapted to extend 55 between the bars forming the rear pair of supporting legs as clearly shown in Fig. 1.

Adjacent the upper ends of each pair of supporting legs and secured to the under side of the board 1 is a cross bar 6 retained thereto by fastening means such as staples 60 7, and connecting the upper ends of the side bars, forming each pair of supporting legs, are rods 8 adapted for rotary movement within longitudinal bores through the cross-bar 6. The side bars 4 and 5 forming the 65 forward pair of supporting legs 2 are provided at a suitable point thereon with semi-circular cut-out portions 9 to permit the side bars to overlie the cross bar 6 when the device is in its folded position. Adjacent the 70 lower free ends of the side bars forming the rear pair of supporting legs 3 there is provided a cross arm 10 for rigidly securing these side arms in spaced apart position, and secured in any desirable manner, and suitably spaced apart, are step member 11, positioned between the side arms, forming the 75 forward pair of supporting legs, whereby the device may be used as a step ladder when the same is in a position as shown in 80 Fig. 2.

A cross bar 12 is positioned between the side arms forming the rear pair of supporting legs 3, and hingedly secured as at 13 to the upper face of this board is an arm member 14 provided with an eye in its outer free end adapted to engage over the hooked end of a retaining member 15, for rigidly maintaining the associated pair of supporting legs in their open position.

As a means for preventing displacement of the forward pair of supporting legs 2 from the position as shown in Fig. 1 when it is desired to move the ironing board from one place to another without folding the 95 same, the above mentioned cross plate 12 is provided adjacent its opposite ends with hook-shaped pivoted bar members 16, these members adapted to securely lock the side bars of this pair of supporting legs in an 100 open extended position as shown in Fig. 1.

A sleeve board 17 is shown slidably positioned within suitably spaced depending L-shaped bracket members 18 upon the under side of the board 1, and as shown by the 105 dotted lines in Fig. 1 this board may be extended to an operative position whereby the sleeves of garments may be conveniently ironed thereon, or when it is not desired to use the sleeve board the same may be slid 110 backwardly beneath the under surface of the said ironing board.

From the above description, it will be readily seen that when the device is in its completely folded position, the supporting legs may be extended into their crossed position as shown in Fig. 1, at which time the pivoted arm member 14 may be swung upward upon its hinge to engage the hook 15 carried by the board 1, and that the swinging hook-shaped plate members 16 may be 10 swung downwardly to engage the hooked ends of these plates beneath the adjacent faces of the side bars forming the forward pair of supporting legs 2 and in which position the device will be substantially rigid so 15 as to be used as an ironing-board. Should, however, one desire to employ my device as a stepladder, the hooked-shaped members 16 are first swung away from the side bars of the forward supporting legs, and the hook- 20 engaging plate 14 is removed from its corresponding hook for permitting the rear pair of supporting legs to be folded upwardly upon the under surface of the board 1 as shown in Fig. 2, the device may be then positioned as 25 shown in Fig. 2 at which time the forward pair of supporting legs having the cross

steps thereon may be employed as a ladder, these supporting legs being themselves supported by the ironing board 1.

While there is herein shown and described the preferred embodiment of the present invention, it is nevertheless to be understood that minor changes may be made therein without departing from the spirit and scope of the invention as claimed. 30 35

What is claimed as new is:

In an ironing board of the type described, a board member, pairs of legs hinged at their upper ends to the underside of the board member and arranged in crossed relation when the ironing board is set up, a cross bar carried by one pair of legs adapted to be engaged by the other pair of legs to hold the board in set up position, cooperating means carried by the cross bar and board member for rigidly supporting the latter, and members pivotally carried by the cross bar adapted to engage one pair of legs to prevent separation of the said pairs of 40 45 50 legs.

In testimony whereof I affix my signature. PAUL WOSS.
